Attorneys

UNITED STATES PATENT OFFICE.

HORACE C. ANDERSON, OF AMARILLO, TEXAS.

HAND STAMP.

Application filed December 22, 1925. Serial No. 77,065.

This invention relates to hand stamps, and particularly to the type known as rubber stamps and has reference more specifically to the handle and its connection with the base or lower portion of the stamp.

An object of this invention is to provide an improved connection between the base of the stamp and its handle for permitting a yielding or compression of the handle in the application of the stamp to a surface for insuring a uniform and even pressure of the stamp at all ends and sides thereof so that even though the hand is not held in true alignment with the surface, the stamp will effect an even impression.

Another object of the invention is to provide a handle with a neck portion of rubber or yieldable substance for connecting the base of the stamp with the handle, and to provide a stiffening element mounted to maintain the neck in proper alignment with the handle and so mounted as to adjust the tension and to permit of the proper equalizing of the base of the stamp to the surface when subjected to pressure.

The invention still further aims to provide an elastic neck portion which is detachably connected at one end to the handle of the stamp and at its other end is compressed to the desired degree against the base of the stamp to support the base on the handle in such position that when pressure is exerted on the handle the neck portion may be compressed axially and at the same time permits the base portion to rock or move upon the lower end of the neck portion to assume its proper position against the surface when the handle is forced toward the same.

A still further object of the invention is to provide a readily detachable neck of flexible material and to provide a coupling carried by the neck to stiffen it against undue lateral bending and to place the neck under desired tension, the connection being independent of the handle to provide the required resilient connection between the parts.

The above and various other objects and advantages of this invention will in part be described in, and in part be understood from the following detailed description of the present preferred embodiment, the same being illustrated in the accompanying drawing, wherein:

Fig. 1 is a vertical central section taken

through a hand stamp constructed according to the present invention.

Fig. 2 is a transverse section taken on the line 2—2 of Fig. 1, and looking downwardly toward the base of the stamp, and

Fig. 3 is a view similar to Fig. 1, showing a slight modification in the structure of the hand stamp.

Referring to the drawing 10 designates a handle of any approved configuration adapted to be grasped in the hand for pressing the stamp downwardly against a surface upon which an impression is to be made. The handle 10 has at its lower end a relatively large axial opening which is internally screw threaded for the major portion of its length but which is unthreaded at its inner or upper end to provide a chamber or space 11.

A neck 12 of rubber or other elastic material has an elongated externally threaded shank at its upper end adapted to be screwed into the opening in the handle and provided with a stop shoulder 13 at the lower end of the shank which abuts the lower end of the handle and limits the insertion of the shank into the handle to leave the chamber or space 11 free. Below the shoulder 13, the flexible neck is provided with a downwardly flaring ring portion 14 which merges into a foot piece 15 flaring annularly from the ring portion 14 and which is provided with a concavity 16 in its under side permitting the spreading and flattening of the foot portion 15 against the upper surface of the base 17 of the stamp.

The concavity 16 is relatively broad and the base portion 17 has a relatively large central opening 18 therethrough which registers with the cavity 16, and with an axial opening which is formed through the resilient neck 12. Secured by an adhesive, or the like, is the body 19 of the stamp which may be of rubber or the like carrying suitable characters or forms by means of which the impression is to be made. The opening 18 through the base 17 is flared or counterbored at its lower end to accommodate an anchoring plug 20 which is of conical form having its apex portion extending upwardly in the opening 18 and with its enlarged portion in the counterbore or countersink of the opening 18. The plug 20 carries an upwardly extending eye 21 at its apex and into which is connected a hook 22 or the like carried on the lower end of a rod 23 which

- serves as a connecting member between the neck 12 and the base 17, and which also provides a stiffening element for the neck 12. The upper end of the rod 23 extends beyond the neck 12 and is screw threaded and receives thereover a washer 24 knurled or roughened at opposite sides to frictionally seat upon the upper end of the neck 12 and to receive thereon a binding nut 25 adjustably threaded on the rod 12 to draw the same upwardly through the neck 12 to the desired extent. The rod and nut provide a tension means for compressing the neck 12 to the desired degree against the base 17 of the stamp.
- 15 The chamber 11 permits the nut 25 and its rod 23 to move upwardly when the handle 10 is forced downwardly with sufficient pressure to further compress the lower end of the neck.
- 20 In Fig. 3 a slight modification is shown wherein the foot piece 26 of the neck is provided with a relatively large concavity 27 for receiving the hook 22 of the rod 23 therein when the base 28 of the stamp is of metal or other relatively thin material. In this instance a relatively shallow tapering plug 29 is secured through a correspondingly formed opening in the base 28 with the eye 30 of the plug engaging the hook 22 and lying within the cavity or recess 27. The stamp or block 31 is secured to the lower side of the base 28 in any suitable manner.
- 25 In use, the binding nut 25 is tightened to compress the foot piece 15 of the neck against the base 17 of the stamp so as to compress the neck to the desired extent and establish a firm connection between the neck and the base. The neck 12 is now screwed into the handle 10. When it is desired to
- 30 make an impression on a surface, the handle 10 is grasped in the usual manner so as to force the stamp 19 against the surface. During this action the foot piece 15 is further compressed against the base 17 and is supported against undue spreading by the ring portion 14, which latter however is also capable of compression and of being spread to a slight extent. During this compression of the lower end of the neck 12, the rod 23 with its nut 25 is permitted to move upwardly into the chamber 11 of the handle so that there will be no rigid connection between the base and the handle.
- 35 Should the pressure of the handle be unevenly applied to the base 17, the rod 23 may swing at its lower end upon the eye 21 so that the base 17 may seat in a position substantially parallel with the surface upon which the impression is made. This swinging or universal action is permissible in the form shown in Fig. 1 by reason of the opening 18 through the base 17, and in the modified form shown in Fig. 3 by reason of the enlarged recess or cavity 27 and the arrangement of the hook 22 and eye 30 therein.

The handle is thus connected to the base of the stamp by an axially compressible connection, and a connection which has universal movement as well as a connection which is reinforced above the joint and which is adjustable as to its rigidity.

It is of course understood that various changes and modifications may be made in the details of construction and design of the above specifically described forms of the invention without departing from the spirit thereof, and being restricted only by the scope of the following claims.

What is claimed is:

1. A hand stamp comprising a handle, a resilient neck carried by the handle, a base provided with a stamp, and a pivoted connection adjustably secured between the base and the neck for initially compressing the latter and holding the base thereto. 80
2. A hand stamp comprising a handle, a resilient neck secured in the lower end of the handle, and projecting beyond the same, a base having a stamp at its lower side, and adjustable means carried by the base and secured through the neck for compressing the latter and binding the base against the lower end of the neck. 90
3. A hand stamp comprising a handle having a threaded opening in its lower end, a resilient neck screwed at one end to said opening, a base fitting against the lower end of the neck, a rod pivotally connected to the base and extending upwardly through the neck, and an adjusting nut carried on the upper end of the rod for drawing the base against the lower end of the neck and compressing the latter to the desired rigidity. 95
4. A hand stamp comprising a handle having a threaded opening in its lower end and a chamber above the opening, a resilient neck threaded into said opening and provided with an intermediate ring portion and a flaring foot piece below the ring portion, a base seated against said foot piece, a rod hinged for universal movement upon the base and extending axially upward through the neck, and an adjusting nut on the upper end of the rod engaging the upper end of the neck for compressing the same against the base, said rod maintaining the neck against lateral bending and said connection permitting the flexing of the foot piece and the swinging of the base to adapt the latter to the surface against which the stamp is pressed. 105
5. A hand stamp comprising a handle having a threaded opening in its lower end, a resilient neck detachably threaded in said opening and having a stop shoulder intermediate its ends to engage the handle and limit the insertion of the neck in the handle, said neck having a reinforcing ring portion below the shoulder and a flaring hollow foot portion below said ring, a base carrying a 110

- 120
- 125
- 130

stamp fitting against said foot portion, said base having an enlarged central opening therethrough, a tapering plug extending upwardly into the opening and having an eye 5 lying in the opening, a rod carried axially in the neck and provided with a hook on its lower end engaging said eye, a washer mounted on the upper end of the neck, and a binding nut carried upon the upper end of 10 the rod and working against said washer to draw the base against the neck and compress the latter.

6. A hand stamp comprising a handle having a threaded opening in its lower end,

a resilient neck threaded at its upper end 15 into the opening of the handle and provided upon its lower end with a flaring hollow foot portion, a base engaging against the foot portion and carrying a stamp, a plug carried by the base and having an eye projecting upwardly into the hollow foot portion, a rod mounted axially in the neck and having a hook on its lower end engaging the eye, and an adjusting nut on the upper end 20 of the rod for drawing the same upwardly 25 through the neck and compressing the latter against the base.
